METAL LIQUID CONTAINER

Frank B. Eilers, Fort Wayne, Ind., assignor to
Tokheim Oil Tank and Pump Company, Fort
Wayne, Ind., a corporation of Indiana

Application February 3, 1933. Serial No. 654,994

1 Claim. (Cl. 220—71)

This invention relates to improvements in metal liquid containers of that type in which lubricating oil or other liquid is held in storage to be dispensed as required, and the walls of which are disposed in flat planes. Such containers, especially when the walls thereof are of thin metal, when filled with liquid tend to expand because of the pressure of the head of liquid within the container against the flat walls thereof which 5 results in false indications of the quantity of liquid in the container when a gauge stick is employed in the ordinary manner of determining the content of the container by ascertaining the level of liquid therein. Outward bulging of the 10 flat walls of such containers, due to the head of the liquid content thereof, causes lowering of the liquid level in the containers with the consequent inaccuracies in measuring the contents of the containers and interference with grouping 15 of a series of tanks together in compact formation.

An object of the invention is to provide a simple expedient for sustaining the flat walls of a metallic liquid container substantially in their normal planes to prevent bulging thereof because of pressure within the container occasioned by the head of liquid therein, or, becoming indented by force externally applied by accident or otherwise which would alter the normal quantity holding 20 capacity of the container.

Other objects and advantages of the invention will appear in the following description.

An illustrative embodiment of the invention is shown in the accompanying drawing, in 25 which:

Fig. 1 is a perspective view of a lubricating dispenser including a liquid container of a type of which the invention is applicable and a pump in connection therewith for withdrawing liquid 30 therefrom;

Fig. 2 is a transverse section of a liquid container in which the invention is embodied;

Fig. 3 is a vertical section of Fig. 2 on the line 3—3 thereof;

Fig. 4 is a side elevation upon an enlarged scale of one of the braces used in the container structure, a portion thereof being broken away;

Fig. 5 is a top plan view of Fig. 4; and

Fig. 6 is a bottom plan view of Fig. 4.

The illustrative embodiment of the invention consists of a liquid container 1 formed of sheet metal and characterized by its walls 2 that extend in flat planes and which are sustained in their 55 respective planes by means to oppose external

and internal pressure to which the container may be subjected.

As an example of the invention the flat walls 2 of the container 1 have secured thereto, upon their respective inner faces, corresponding ribs 3 formed conveniently of sheet metal shaped to have divergently disposed contiguous sides 4 that terminate, along the edges thereof opposite their juncture, with outwardly extending flanges 5. Preferably, the sides 4 are of greater width at 60 their lower ends than the tops thereof so that the ribs are tapered more or less from their lower ends toward their tops. By this formation of the ribs, after being installed permanently in connection with the flat walls afford greater resistance to outward pressure against the walls of the head 65 of liquid in the container in the lower portion of said container where the normal pressure is comparatively greater than the upper portion thereof.

The ribs are vertically disposed within the container and the flanges thereof are permanently secured to the inner faces of the walls 2 by any suitable expedient, such as by spot welding or other convenient means whereby said flanges are 70 intimately secured to the corresponding walls at frequent intervals or throughout their entire 75 lengths. Thus, a vertical passageway 4' is left between the sides 4 of each rib and the adjacent portion of the wall 2 to which the rib is secured 80 that is open at each end of the rib.

Each rib 3 terminates at its top and bottom at corresponding points suitably spaced from the top 6 and bottom 7 of the container so as to admit of free flow of liquid in the container into 85 and from the passageways. Thus, displacement 90 of liquid in the container by the ribs is limited to the extent of the volume of metal forming the ribs.

In the drawing, the container 1 is shown with a dispensing pump 8 superimposed thereon having a suction pipe 9 extending into the container through which liquid in the container is withdrawn therefrom as required by operating the pump, and the container is also provided in its top 6 with a fill opening 10 for replenishing the 95 container with liquid to be subsequently dispensed.

In use, when the container is filled with liquid the more or less extensive walls thereof to which the ribs have been applied are maintained substantially in their normal planes and are prevented from outward as well as inward displacement so that the normal holding capacity of the 100 container is thereby maintained, and the walls 110

of the container are braced by the ribs and held so as to permit the grouping of a series of containers together without interference with each other due to bulging of adjacent walls thereof.

5 I claim:

In combination with a sheet metal container for liquid having walls that extend substantially in flat planes, a series of ribs each being formed of sheet metal and shaped so as to have divergently disposed sides, the inner edge of one of which sides is contiguous with the correspond-

ing inner edge of its complemental side, and the edge of each side having an outwardly extending flange, said sides being comparatively wider at their lower ends than at their upper ends, said flanges being secured to the inner face of the container wall, the space between the sides of said rib and the adjacent portion of the container wall constituting a passageway that is open to the interior of the container at each end of the rib.
